Inventor:

Leo J. Grubman,
By his Attorney, Leo McNaught

UNITED STATES PATENT OFFICE.

LEO J. GRUBMAN, OF NEW YORK, N. Y., ASSIGNOR TO GRUBMAN ENGINEERING AND MANUFACTURING CO. INC., OF NEW YORK, N. Y., A CORPORATION OF NEW YORK.

SOUND-PRODUCING DEVICE FOR DOLLS, ETC.

Application filed November 18, 1922. Serial No. 601,725.

To all whom it may concern:

Be it known that I, LEO J. GRUBMAN, a citizen of the United States, and a resident of the borough of Bronx, county of Bronx, 5 city and State of New York, have invented certain new and useful Improvements in Sound-Producing Devices for Dolls, Etc., of which the following is a specification sufficient to enable those conversant with 10 the art to which the invention appertains to utilize the same.

My improvements relate to the type of sound producing appliances for use in toys, and particularly dolls, etc., of which one 15 example is disclosed in my concurrent application Serial No. 542,884, filed March 11th, 1922. As in that case, the object of my present invention is the production of a simple, substantial, compact, "self-contained" device of the character designated having no extraneous parts, and which is 20 gravity-automatic in action in the sense that the use of springs is obviated, and in that no external pressure is necessary for 25 sound production—the objects of my present improvements as related to the structure disclosed in the aforesaid application Serial No. 542,884, being the perfection and amplification of sound production, and certain 30 structural advantages incidental to standardization of manufacture. The important feature of my present disclosure resides in the provision of simple, effective 35 and easily applied means for fixedly securing certain parts of the mechanism enclosed within the outer shell or casing to the opposite ends of the shell wall whereby the use of glue or other adhesive may be dispensed with. In the present embodiment 40 of my invention I propose to provide the marginal portion of the metallic end plate closing one end of the casing with suitably formed means for clamping engagement upon the end of the bellows wall and over 45 the end edge of the casing wall, whereby said means subserves the two-fold purpose of securely fixing the end plate in place and also tightly clamping and securing the end of the bellows wall to the casing wall.

Another object of my present improvements is to provide within one end of the casing or housing a sound amplifying wall or partition which is fixed at its edge to

the casing wall by means on the other end plate of the casing similar to that securing the bellows wall in place and which provides a sound receiving chamber of comparatively restricted and definite dimensions so that the sound will finally issue from the device in substantially constant 60 volume.

With the above and other objects in view, the invention consists in the improved combination, arrangement and construction of the several elements as will be hereinafter 65 more particularly described, illustrated in the accompanying drawings and subsequently incorporated in the subjoined claims.

In the accompanying drawings I exemplify a preferred and practical embodiment of the essential features of my invention, although I do not limit myself to the identical form and construction of parts shown, since modifications in minor details, and equivalent mechanical expedients may 70 be resorted to with like result, and without departing from the spirit and intent of my invention in this respect.

With this understanding,

Fig. 1, represents a side elevation of my 80 improved sound-producing device;

Fig. 2, is an elevation of the emission end of the device;

Fig. 3 is a plan view of one of the end 85 plates for the shell or casing;

Figure 4 is a similar view showing the reverse side of said end plate;

Fig. 5, is a central sectional elevation of the device taken upon line 5—5, Fig. 2;

Fig. 6, is a similar view, with the device in reversed position as related to Fig. 4, and with the bellows expanded;

Fig. 7 is a plan view of the movable bellows head;

Fig. 8, is a central sectional elevation of the device, reversed as related to Fig. 6, with the operative parts positioned preparatory to the collapse of the bellows;

Fig. 9, is a transverse section taken upon plane of line 9—9, Fig. 8;

Fig. 10, is an elevation of the concave side of the intensifying partition;

Fig. 11, is a transverse central section taken upon plane of line 11—11, Fig. 10;

Fig. 12, is an elevation of the convex side 105 of the intensifying partition;

Fig. 13 is a plan view of the end plate shown in Fig. 2 looking at the reverse side thereof;

Fig. 14, is a side elevation of the movable bellows head;

Fig. 15, is a detail view of the sound emission pipe or tube.

As heretofore, the operative parts of my sound-producing device are enclosed in a rigid casing, consisting, in the preferred construction as shown by way of exemplification in the accompanying drawings, of a cylindrical shell c , closed at one of its ends by the disc c' , and at its other end by an apertured plate or disc c^2 . The external configuration of the box or casing is of secondary consideration, its function being simply to isolate and protect said operative parts, and to afford fixed external dimensions, in such manner as to render the device considered in a unitary sense, self contained, and without protuberant parts. In this connection, it is obvious that the container or casing c , c' , c^2 , might be other than cylindrical in shape with substantially like results, although the form of casing shown is preferable for simplicity, compactness and cheapness of structure.

The head plate c^2 , of the casing is formed with one or more apertures a^3 , for communication with the atmosphere. However, it will be apparent that communication with the atmosphere might be provided for through the upper portion of the cylindrical shell c , adjacent to the head plate c^2 , or elsewhere, if found expedient, with like result, in that provision is thus made for inlet and outlet of air and of sound vibrations.

The sound emission pipe a , which also functions as a guide and lateral support for the free or movable head b , of the bellows B , is likewise preferably, but not necessarily of cylindrical form, and positioned centrally as related to the casing and bellows, and is fixedly secured to and between the casing end plates c' , and c^2 , as shown more particularly in Figs. 5, 6, and 8, of the drawings. Hence, it may consist of a tube a , held in plate at one extremity by a depression c'' , in the plate c , and at the other extremity by the edge of the central opening c^{22} , in the plate c^2 , fitting in an annular groove a' , (Figs. 8 and 15) formed in the peripheral surface of said wind pipe a , adjacent to one end thereof, the extreme outer edge of the tube being peaned or bent over the outer surface of said plate c^2 , thereby locking the wind pipe in place. This construction is shown in Figs. 5, 6, 8, and 15, of the drawings, Fig. 15, illustrating the method of attachment of the tube end to the plate c^2 . A plug-disc a^2 , fitting snugly within the latter end of the pipe a , not only closes and seals that extremity thereof, but also reinforces and sustains the joint between the

pipe a , and the plate c^2 . The other extremity of the pipe a , is closed and sealed by the aforesaid depression c'' , of the disc c , within which depression c'' , the lower end of the pipe fits, making a tight joint therewith. Within the latter end of the pipe a , is positioned a reed r , or equivalent sound producing element supported in the plug r' , the side of the tube adjacent thereto, and between it and the inner side of the disc c' , being formed with one or more apertures a^4 , through which communication is established between the interior of the bellows B , and said pipe a , so as to afford adequate means for the admission of air to, and its expulsion from, the interior of the bellows B , in the operation thereof.

Air is admitted to or expelled from, the pipe or tube a , through the medium of the apertures a^3 , a^4 , which communicate with the sound receiving chamber a^5 , between the apertured plate c^2 , and the resonator or sound intensifying partition P , which latter is rigidly positioned within the casing and as related to said plate c^2 , as shown more particularly in Figs. 5, 6 and 8, of the drawings.

Said resonance partition P which controls the final emission of sound through the apertures c^3 , is preferably of concave form on the side thereof opposed to the apertured plate c^2 , of the casing as shown in the drawings, so as to concentrate and align the sound waves or vibrations emanating from the wind chest in a manner essentially parabolic, although I do not limit myself in this respect, since the main function of said partition P , is to definitely limit the area of the sound receiving chamber a^5 of the device and separate it from the rest of the interior of the casing, it having been found that otherwise the collapse of the bellows causes the movable head b , thereof to attenuate the sound vibrations by enlarging the area between it and the perforated end plate, thus materially modifying the sound emanation in such manner that the second syllable produced is less distinct than the first. In other words, the essential feature of my invention in this respect consists in interposing between the apertured plate c^2 , of the casing, and the movable head b , of the bellows B , a fixed partition P , which prescribes the area of sound deflection and confines it to the space adjacent to the emission end of the pipe or tube a , and between aperture a^4 and the aforesaid apertured plate c^2 , as shown in Figs. 5, 6 and 8, of the drawings.

The said resonance partition P , is formed with a central opening p , for the accommodation of the pipe or tube a , and it may be fixedly attached to the casing in any suitable manner, a preferred method being shown in Figs. 5, 6 and 8, of the drawings, in which said partition P , of concavo-con-

- vex shape in cross section is formed with a peripheral flange p' , which is interposed between the end edge of the cylindrical shell c , and the channelled circumferential edge 5 c^{23} , of the plate c^2 , which is provided with an inturned bead clinched in the exterior surface of said shell c , thereby securing both the head plate c^2 , and the partition P , rigidly in position.
- 10 In a similar manner the one end edge of the flexible member b^x , of the bellows is secured to the opposite end of the cylindrical casing c , by means of the end plate c' , the circumferential edge of which is formed 15 with a channel bead clinched against the outer surface of said casing shell c , with the lower edge of said flexible member b^x , interposed between said plate and the shell wall, as clearly indicated in said Figs. 5, 6, 20 and 8, of the drawings.
- The other end edge of the flexible member b^x , of the bellows is attached to a circumferential flange b^2 , on the movable bellows head b , by means of a clamping ring b^3 , this 25 method of attachment being inexpensive and effective, and the jointure being attained thereby in a simple manner. Thus it will be noted that the ring b^3 positively clamps the end edge portion of the flexible bellows 30 wall against circumferential angularly related surfaces of the bellows head, and that one of these surfaces acts to positively limit the axial movement of this ring relative to the head to its effective clamping position 35 upon the end edge of the bellows. By thus clamping the flexible bellows wall against the two angularly related surfaces of the head, greater security is obtained with less liability of the end of the bellows wall be- 40 coming detached from said head and also a more perfect air tight seal is assured. Should one of said surfaces of the movable bellows head contain imperfections, the es- 45 cape of air would nevertheless be prevented by the tight frictional clamping contact of the bellows wall with the other surface of said head. Also, I have found that the use of such a frictional clamping connection between the flexible bellows wall and the 50 movable head greatly expedites the assem- blage of the parts over that incident to the use of glue or other adhesives and also reduces manual labor to a minimum.
- The bellows head b , is provided with 55 sound control means having valve ports b^5 , b^6 , and functions substantially as set forth in my concurrent application Serial No. 542,884, hereinbefore referred to.
- It will be noted that one end edge of the 60 flexible bellows wall is turned inwardly over the margin of the bellows head b and clamped thereto while the other end edge of said flexible bellows wall is turned outwardly around the end edge of the casing wall 65 and secured thereto by the plate c' which
- constitutes a common closure for this end of the casing and the bellows chamber. However, it is not essential in practice that the form of this closure plate shown in the drawings, shall be strictly adhered to, 70 though I prefer to provide this plate, whatever its form may be, with a part constituting a stop by reason of its coaction with the end edge of the casing wall to prevent the possibility of said plate being forced 75 into the casing.
- I have found that the turning of the end edges of the flexible bellows wall in reverse directions over the edge of the air expelling head and the casing end respectively is of 80 material advantage in facilitating the easy and rapid assemblage of the parts of the bellows structure in connection with the casing wherein this bellows is housed or enclosed. 85
- It will also be understood that the particular form in which the partition P is illustrated in the accompanying drawings is not essential to the proper operation of the device, and this partition might be otherwise constructed and mounted within the casing end, the essential consideration being that the partition or its equivalent shall be interposed between the sound emission aperture a^4 and the movable bellows 90 head so as to separate that end portion of the interior of the casing from the portion within which the bellows head moves and thereby provide a sound receiving space of constant and unchanging dimensions. The 95 partition b thus provides a confining and directing means for the sound waves so that the latter issue from the apertures c^3 in substantially equal volume each time the emission opening a^4 is uncovered in the air expelling movement of the bellows head. Thus a more realistic simulation of the 100 spoken pronunciation of word syllables is produced than would be the case, if such partition or its equivalent was omitted, and the area of the casing chamber into which the sound is emitted through the aperture a^4 constantly increased during the air expelling movement of the bellows head. 105
- From the foregoing it will be manifest 110 that I have produced a device of this kind in which notwithstanding the very simple and compact arrangement of the parts of the sound producing mechanism within a housing or casing of relatively small dimensions, there will be produced in a positive manner a very realistic simulation of the desired word syllables. Therefore, since it is manifest that the essential characteristics of my present improvement might be 115 exemplified in numerous other alternative structures, it is to be understood that I reserve the privilege of adopting all such legitimate changes in the form, proportion and relative arrangement of the several 120
- 125
- 130

parts as may be fairly embodied within the spirit and scope of the invention as claimed.

What I claim as my invention and desire to secure by Letters Patent is,

6. 1. In a sound producing device, a casing, sound producing means enclosed within said casing including a flexible bellows wall, and end plate closing one end of the casing and the bellows chamber and having means 10 clampingly engaged over the end edge of the casing wall and with an end edge of the bellows wall to fixedly secure the latter in place.
15. 2. In a sound producing device, a casing, sound producing means enclosed within said casing including a flexible bellows wall, and an end plate having marginal means coacting with an end edge of the bellows wall and with the end edge of the casing wall 20 and constituting a common means for fixedly securing said plate and the end edge of the bellows wall with relation to said casing wall.
25. 3. In a sound producing device, a casing, sound producing means enclosed within said casing, including a flexible bellows wall, and an end plate closing one end of said casing having a marginal channeled bead clinched upon one end edge of the bellows wall and 30 the end edge of the casing wall and constituting a common means fixedly securing both said plate and the end of the bellows wall with relation to the casing wall.
35. 4. In a sound producing device, a casing, sound producing means enclosed within said casing including a bellows having a flexible body wall and a sound emission tube extending through the bellows chamber, a closure plate for one end of the casing provided 0 with means coacting with one end of said tube to retain the same in fixed relation to the casing, and said plate also having marginal means to clampingly secure one end of the flexible bellows wall around the 5 end edge of the casing wall and to retain said closure plate in its applied position.
45. 5. In a sound producing device, a casing, sound producing means enclosed within said casing including a flexible bellows wall, a closure plate for one end of the casing having its body portion positioned in a plane inwardly of the end edge of the casing wall and formed with a channeled marginal bead clampingly engaged around said end edge of the casing wall and upon the end of the flexible bellows wall whereby said closure plate and the end of the bellows wall are fixedly held with relation to the casing wall.
55. 6. In a sound producing device, a casing, sound producing and controlling means wholly enclosed within said casing, and end plates for said casing each provided with means for fixedly securing said plate and a part of the sound producing and controlling means to one end of the casing wall.
7. In a sound producing device, a casing, sound producing means enclosed within said casing including a flexible bellows wall, a closure plate for one end of the casing having means for securing one end edge of the bellows wall in clamping engagement over one end edge of the casing wall, a partition wall arranged in the other end of the casing forming a sound deceiving chamber, said partition wall having a marginal flange 75 engaged upon the opposite end edge of the casing wall, and a second closure plate for the latter end of the casing having marginal means for clamping engagement over said end edge of the casing wall and upon the flange of said partition wall.
8. In a sound producing device, a casing, sound producing means enclosed within said casing including a flexible bellows wall fixed at one of its ends to the casing wall, a movable air expelling head secured to the other end of said flexible bellows wall, and a concavo-convex partition wall arranged in the casing between the opposite end thereof and said movable bellows head and forming a 85 sound receiving chamber.
9. In a sound producing device, a casing, sound producing means enclosed within said casing including a bellows having a flexible body wall, sound producing and emitting means extending axially through said casing and the bellows chamber, a closure plate for one end of said casing having means to secure one end of the bellows wall to the casing wall, a gravity movable head fixed to the opposite end of the bellows wall and movable along said sound emission means, a concavo-convex sound amplifying wall extending within the casing between the opposite end thereof and the movable bellows head, and a closure 90 plate for the latter end of the casing having means coacting with said partition wall to secure the same in fixed relation to the casing wall.
10. In a sound producing device, a casing, sound producing means enclosed within said casing including a flexible bellows wall fixed at one of its ends to the casing wall, a movable air expelling head secured to the other end of said flexible bellows wall, sound producing and emitting means having an emission aperture spaced from the opposite end of the casing, and a partition wall located between said emission aperture and the movable air expelling head and fixed at its outer edge to the casing wall, said partition wall 100 constituting a sound confining and directing member.
11. In a sound producing device, a casing, sound producing means enclosed within said casing including a bellows having a flexible body wall, a movable air expelling head fixed to one end of said wall, and a common closure member for the other end of the bellows chamber and one end of said casing.

12. In a sound producing device, a casing, sound producing means enclosed within said casing including a bellows having a flexible body wall, a movable air expelling head fixed to one end of said wall, and a common closure member for the other end of the bellows chamber and one end of said casing, said closure member having a part bearing upon the end edge of the casing wall and preventing movement of said member into the casing. 30
13. In a sound producing device, a casing, sound producing means enclosed by said casing including a flexible bellows wall, an air expelling head fixed to one end of said wall, the other end of said bellows wall being outwardly turned around one end edge of the casing wall, and a common closure member for the latter end of the casing and the bellows chamber having a part overlying the out-turned end edge of the bellows wall and constituting a stop coacting with the casing wall to prevent movement of said member into the casing. 35
14. In a sound producing device, a casing, sound producing means enclosed by said casing including a flexible bellows wall, an air expelling head, one end edge of said flexible wall being inwardly turned over the margin of said head and secured thereto and the other end edge of said flexible wall being outwardly turned over an end edge of the casing wall, and means for closing the latter end of the casing and fixing the edge of the bellows wall thereto. 40
15. In a sound producing device, a casing, sound producing means enclosed within said casing including a bellows having a flexible body wall, a common closure member for one end of the bellows and said casing and frictional clamping means for effecting an air tight seal between said member and the flexible body wall of the bellows, a gravity movable head for the other end of the bellows, frictional clamping means connecting the latter end of the flexible body wall of the bellows to said head, and a sounding reed through which the air is expelled from the bellows in the gravity movement of said head. 45
